CATHODE-RAY TUBE

Johannes de Gier, Eindhoven, Netherlands, assignor to Hartford National Bank and Trust Company, Hartford, Conn., as trustee

Application April 6, 1951, Serial No. 219,550
In the Netherlands May 2, 1950

6 Claims. (Cl. 313—82)

1

This invention relates to cathode ray tubes for television reception.

Such tubes often employ an ion trap to separate the negative ions, which are emitted by the cathode together with the electrons or which are produced in the discharge space, from the electron beam, in order to avoid a so-called ion spot on the image screen. Such an ion trap employs means to deflect the electrons from their initial direction in which the ion beam maintains its initial direction, but alternatively the ions may be deflected in the same direction as the electrons, the separation of ions and electrons being effected by deflecting the electrons again into their initial direction.

This particular construction avoids another disadvantage, which is generally inherent in cathode-ray tubes which are not provided with a deionisation device, but which is also found in tubes provided with an ion trap.

Direct light of the cathode visible on the screen of the cathode-ray tube has in the past been objectionable. In order to avoid the reflection of the light produced by the screen on the photo-electric cathode in image transformers, these two elements, instead of being arranged in parallel have been arranged at an angle in such manner that the light of the collecting screen no longer reaches the photo-electric cathode and such that the electrons are conveyed along curved paths from one element to the other. In order to avoid the ion spot, similar precautions have been taken with cathode ray tubes, but in this case the tube was given a curved construction which was manufactured with difficulty, the arrangement of cylindrical coils, i. e. focussing coils, being difficult.

It has been found that the type of screen bears to some extent upon the nature of the phenomenon. The disadvantage is more apparent in the case of thin collecting screens, which transmit a great quantity of light. Consequently, it is not possible to employ certain types of screens, and, moreover due to the harmful phenomenon there is a tendency to construct the screens with greater thickness than is useful and necessary for the optimum image reproduction.

A further disadvantage is that cathode light is concentrated on a comparatively small portion of the screen and the reddish colour of the light forms a strong contrast against the blue-white light of the luminescent screen. Finally, it is practically impossible to use cathodes with higher operating temperatures than those at which oxide-cathodes operate in cathode-ray tubes for television reception.

2

It is an object of the invention to eliminate cathode light in cathode-ray tubes for television reception.

According to the invention one or more transverse walls provided with an aperture are arranged in the path transversed by the electrons from the cathode to the area where they leave the final anode in such manner that the part of the cathode which is intended to be heated to the temperature at which electron emission takes place is not visible from any point of the collecting screen.

Fig. 1 shows one form of light shield according to the invention;

15 Fig. 2 shows another embodiment of a light shield according to the invention;

Fig. 3 shows an electron beam focussing system in conjunction with a light shield;

10 Fig. 4 shows another electron beam focussing system with a light shield;

Fig. 5 shows a cathode-ray tube employing a light shield according to the invention.

Fig. 1 of the drawing shows one form of ion trap for separating ions from the electron beam 25 in a cathode ray tube which comprises a cylindrical electrode 1 which embraces the electron beam emitted by a cathode 2.

Fig. 2 of the drawing shows one form of ion trap 30 for separating ions from the electron beam in a cathode ray tube which comprises a cylindrical electrode 1 which embraces the electron beam emitted by a cathode 2. This electrode, which is hereinafter referred to as an "ion collector" has a transverse wall 3 (collecting plate), having an aperture 4 to allow the electrons to pass therethrough. The cylindrical part of the ion collector may be a metal body arranged in the tube, and need not necessarily have a circular section. Alternatively, it may be constituted by a conductive coating or a metal part 35 of the tube wall.

The aperture 4 in the collecting plate 3 is usually circular and concentric with the axis of the ion collector, but neither of the aforementioned requirements for the aperture is absolutely necessary.

40 The end surface at the left-hand end of the cylinder 1 is at an angle to the axis 5 of the cylinder. At this end the electrode 6 is located, the end of which facing the cylinder is at a similar angle to the axis 5 so that a narrow gap is formed between these two parts in which a potential difference between the electrode 6 and the cylinder 1 produces an electric field, which has a 45 constant component in the area covered by the beam at right angles to the axis 5, parallel to the plane of the drawing. The other end of electrode 6 is closed by a diaphragm 7 having a central aperture 8. The cathode 2 is surrounded by a 50 Wehnelt cylinder 9, provided with a diaphragm

10, having a central aperture 11. The beam 12 composed of electrons and negative ions is deflected in the direction of the arrow in the electric field between the electrode 6 and the cylinder 1. The deflecting action of the electric field on the electron beam is neutralized by magnetic forces at right angles to the plane of the drawing. These forces do not change the direction of the ions, so that the ion beam ends at the inner wall of the cylinder 1.

Where the magnetic forces are strongest, the deflection of the electron beam from the axis 5 of the cylinder 1 is greatest. A transverse partition 13 is arranged at this point in cylinder 1 which is provided with an eccentric aperture for the passage of the electron beam 14. By choosing the point where the magnetic forces are acting it may be readily ensured that the eccentricity of this aperture is sufficient so that, viewed from the cathode, the aperture in the collecting plate 5 is completely screened by the transverse partition 13.

It is only necessary that the extension of the line connecting the bottom point of the aperture 4 and the top point of the aperture 14 constitute the bottom boundaries of the apertures 3 and 11 in the diaphragm 1 and 10. Consequently, the top part of the collecting plate 3 and the bottom part of the partition 13 may be omitted if desired. The latter may be constituted by a strip of a width equal to the diameter of the aperture in the collecting plate.

Referring to Fig. 2 the ion collector comprises a broken cylinder 15, having a circular sectional area and closed at the left-hand end by a diaphragm having a circular aperture 17. At the side thereof the Wehnelt cylinder 18 and the cathode 19 are arranged. The beam 20 composed of electrons and negative ions enters the cylinder through the aperture 17. A magnetic field operates in the broken part of the cylinder, the lines of force of which are at right angles to the plane of the drawing. The electron beam 20 is deflected by this field in the direction of the arrow through an angle such that the axis of the beam finally passes through the center of the aperture 21 in the collecting plate 22 and is at right angles to the plane of the collecting plate. The ions being substantially not influenced by the magnetic field continue travelling in the same direction in the bend of the cylinder, so that they strike the wall of the cylinder.

A screen 24 is arranged in the bend of the cylinder which is by-passed by the electron beam and which intercepts the cathode light in the direction of the aperture 21 in the collecting plate 22. Since the screen is arranged in the electrically field-free space inside the cylinder, it can extend near to the path of the electrons, without acting upon the latter.

In the embodiment shown in Fig. 3 the beam composed of electrons and negative ions passes from the cathode through an immersion lens system, comprising control-electrode 26 and accelerating anode 27. Between cylinders 28 and 29 an electric field is produced, which concentrates and focuses the electrons. The cylinder 28 has a diaphragm 29, which circumscribes the beam and which has a central aperture 30. Beyond the diaphragm 29 magnetic forces operate at right angles to the plane of the drawing through part of the path of the electron beam between the diaphragm 29 and the collecting plate 31. The electron beam is thus deflected, the negative ions continue in their initial path

and strike the collecting plate 31. This collecting plate is provided with a non-central aperture 32 located so far distant from the center of the electrode that it lies in the shadow of the diaphragm 29 outside the cone of cathode light circumscribed by the aperture 30.

In the embodiment of the electrode system shown in Fig. 4 the separation of negative ions from the electron beam occurs near cathode 33. Under the action of the combined influence of a magnetic lens field produced by the coil 34 and the electro-static field between control electrode 35 and accelerating electrode 36 the electrons follow strongly converging paths. The negative ions are subjected only to the action of the electro-static field and thus the ion beam is made less convergent. The ion beam is indicated by a broken line whereas the path of the electrons is indicated by a full line. Collecting plate 37 is arranged at a predetermined distance from the cathode and intercepts the ion beam. The point at which the collecting plate 37 is located is chosen so that the sectional area of the ion beam is small relative to the sectional area of the electron beam, which is strongly spread in this area. The collecting plate intercepts not only the negative ions but also part of the electron beam, but this part may be small with respect to the total electron current. The electrons are concentrated in a focus by an electrostatic lens field between accelerating electrode 36 and final anode 38. The final anode 38 is provided with a circumscribing diaphragm 39, having an aperture 40. The area of this diaphragm is chosen so that, viewed from the cathode, the aperture 40 is completely screened by the collecting plate 37.

The various electrode systems are adapted to be arranged in the straight cylindrical neck of a cathode-ray tube of the conventional construction. The system shown in Fig. 3 is arranged at an angle to the tube axis 41 as shown in Fig. 5, provisions being taken that the axis 41 of the tube 42 coincides with the axis of the electron beam. Hence the axis of the tube is chosen to pass through the center of the aperture 32 in the collecting plate 31. Apart from the coils providing the magnetic forces to deflect the electron beam and designated 43, are a focussing coil 44 and deflection coils 45. The latter supply the magnetic fields to deflect the beam in two directions at right angles to one another in order to scan the collecting screen.

While the invention has thus been described in specific embodiments, other modifications thereof will be readily apparent to those skilled in the art without departing from the spirit and scope of the invention as defined in the appended claims.

What I claim is:

1. A cathode-ray tube for television reception comprising an electron gun including a cathode for generating an electron beam, an ion trap in the path of the beam and positioned to intercept ions in the electron beam by deflecting the electrons in a curved path, a transverse wall provided with an aperture therein in the path of the electron beam, and a transverse wall element located between said cathode and said aperture in said transverse wall for interrupting the path of light-rays radiated by said cathode whereby said light-rays are unable to pass through said aperture.

2. A cathode-ray tube for television reception comprising an electron gun including a cathode for generating an electron beam, an ion trap in

the path of the beam and positioned to intercept ions in the electron beam by deflecting the electrons in a curved path, said ion trap comprising a hollow cylindrical electrode having a transverse wall element with an aperture therein for the passage of the electron beam, a transverse wall provided with an aperture therein in the path of the electron beam, and a transverse wall element located between said cathode and said aperture in said transverse wall for interrupting the path of light-rays radiated by said cathode whereby said light-rays are unable to pass through said aperture.

3. A cathode-ray tube for television reception comprising an electron gun including a cathode for generating an electron beam, an ion trap in the path of the beam and positioned to intercept ions in the electron beam by deflecting the electrons in a curved path, said ion trap comprising a hollow cylindrical electrode having a given axis, means to direct the electron beam into said cylindrical electrode at a given angle with said axis, a transverse wall element forming part of said cylindrical electrode and having an aperture for the passage of electrons in said beam, and a second transverse wall element forming part of said cylindrical electrode and provided with an aperture therein in the path of the electron beam, the aperture in said second wall element being located at a point at which the path of the electron beam is parallel to the said axis whereby the electron emissive portion of the cathode is not visible from the side of the second transverse wall portion remote from the gun.

4. A cathode-ray tube for television reception comprising an electron gun including a cathode for generating an electron beam, an ion trap in the path of the beam and positioned to intercept ions in the electron beam by deflecting the electrons in a curved path, said ion trap comprising a first hollow cylindrical electrode portion having a given axis and a second hollow cylindrical electrode portion having an axis, a first transverse wall element at the junction of said first and second electrode portions having an aperture therein for the passage of electrons in said beam, and a second transverse wall portion provided in the second cylindrical electrode portion and provided with an aperture therein in the path of the electron beam, the aperture of said second transverse wall portion being located at a point at which light-rays radiated by said cathode are unable to pass through said aperture.

5. A cathode-ray tube for television reception comprising an electron gun for generating an

5 electron beam, an ion trap in the path of the beam and positioned to intercept ions in the electron beam by deflecting the electrons in a curved path, said ion trap comprising a hollow cylindrical electrode, a first transverse wall portion in the path of the beam and having an aperture for the passage of said beam, and a second transverse wall portion provided with an aperture therein in the path of the electron beam, the aperture in the second wall element being positioned to block visual alignment with the first wall element and the cathode whereby the electron gun emissive portion of the cathode is not visible from the side of the transverse wall remote from the gun.
